FRANCIS T. FRACKER, OF BOSTON, MASSACHUSETTS, ASSIGNOR TO
P. AND F. CORBIN, OF NEW BRITAIN, CONNECTICUT.

Design No. 3,354, dated January 26, 1869.

DESIGN FOR A HINGE.

The Schedule referred to in these Letters Patent and making part of the same.

To all whom it may concern:

Be it known that I, FRANCIS T. FRACKER, of Boston, in the county of Suffolk, and State of Massachusetts, have invented or produced a new and original Design for Hinges; and I do hereby declare the following to be a full, clear, and exact description of the said design, reference being had to the annexed drawing, making part of this specification, wherein—

Figure 1 represents a hinge open, with my design applied to one of the faces thereof, and

Figure 2 is a similar view, showing the design placed upon the back of the hinge.

It is to be understood that, usually, the same design will be applied to the surfaces of both leaves of the hinge.

The hinge represented is a two-part slip-hinge, with a pin projecting from the boss *a* into a hole in the boss *b*, with a washer, *c*, between, and ornaments, *d d*, at the ends of the bosses. My design, however, does not relate to either of these parts, nor to the size or character of the hinge.

My design consists in the ornamentation of the surface of the leaves of the hinge, by recessing such hinge and forming an imitation of lace-work at the bottom of such recessed surface, as at *e e*, and upon this placing or forming the ornamental scroll-work, *i i*, substantially as shown in the drawing, the surface of such ornamental scroll-work being level, or nearly with the surface of the leaves of the hinge.

What I claim, and desire to secure by Letters Patent, is—

The design of the ornamentation, substantially shown in the drawing, to be formed in the surface of the hinge.

In witness whereof, I have hereunto set my signature, this 29th day of December, A. D. 1868.

FRANCIS T. FRACKER
